UNITED STATES PATENT OFFICE.

MAURICE W. REEDY, OF AURORA, ILLINOIS, ASSIGNOR OF ONE-HALF TO FRED B. SHEARER, OF AURORA, ILLINOIS.

RAILROAD SIGNAL SYSTEM.

1,335,919.

Specification of Letters Patent.

Patented Apr. 6, 1920.

Application filed February 27, 1919. Serial No. 279,531.

To all whom it may concern:

Be it known that I, MAURICE W. REEDY, a citizen of the United States of America, and a resident of Aurora, county of Kane, and State of Illinois, have invented certain new and useful Improvements in Railroad Signal systems, of which the following is a specification.

The main objects of this invention are to provide an improved form of mechanically operated automatic signal system for railroads; to provide improved mechanism for controlling the operation of the signal means; and to provide improved means for automatically stopping a train in case it passes a signal set to indicate a closed block.

Illustrative embodiments of this invention are shown in the accompanying drawings, in which—

Figure 1 is a side elevation, partly sectional, of one of the signal-operating mechanisms.

Fig. 2 is a plan of the same.

Fig. 3 is a diagrammatic view illustrating the arrangement of the signaling system along the track.

Fig. 4 is a similar view showing the arrangement of the mechanism when used in connection with street crossings for signaling to pedestrians the approach of a train.

Fig. 5 is a detail of a modified form of means suitable for holding the tripping mechanism depressed for a certain period of time after the train passes thereover.

Fig. 6 is a side elevation of a modified form of signal-operating mechanism.

Fig. 7 is a section taken on the line 7—7 of Fig. 6.

Fig. 8 is a section taken on the line 8—8 of Fig. 6.

The signal system hereinafter described, as applied for signaling trains on the same line of track, comprises a plurality of signals A, B, C, et cetera, Fig. 3, located at intervals along the track, each of which is adapted to be operated by a tripping mechanism A', B', et cetera, also arranged at intervals along the track in advance of the respective signals, to which they are connected by means of cables.

The arrangement of the tripping mecha-

nisms is such that a train in passing over one actuates it so as to set a signal for the purpose of indicating to a following train that a certain block is occupied. Means secure each tripping mechanism in its retracted position until the train passes over and actuates the next tripping mechanism, whereupon, simultaneously with the setting of the corresponding signal, the first tripping mechanism is released so that the signal actuated thereby is returned to its neutral position. In conjunction with each of the tripping mechanisms, means are arranged so that if the engineer of a train, accidentally or intentionally, ignores and attempts to pass a signal set against him, said means will be thrown into position to shift an air valve on the train for the purpose of setting the air brake mechanism and bringing the train to a stop.

In the specific embodiment herein shown, the signals A, B, C, et cetera, are in the form of targets 1 each carried on a rod or shaft 2 journaled in a standard 3 so that it may be shifted through an angle of 90° into and out of a position transverse to the line of track and thereby be exposed to view to the engineer of an approaching train. A spindle 4 is arranged on the upper end of the shaft 2 on which to support a lantern for signaling at night.

The tripping mechanisms each comprise a tripper arm 5 arranged adjacent to the rail 6, so as to be actuated by a train passing thereover, and connected by links 7 and 8 to a drum 9 from which a cable 10 leads to a target 1 at the rear thereof. The tripper arm 5 is pivoted at 11 to a bearing 12 independently of the rail 6 and is disposed along the inside of the rail and normally urged upward so as to be engaged by the flange of a wheel on the train. It is normally urged upward by means of a spring 13 acting on a plunger 14 slidably mounted in a cylinder 15 and connected by a link 16 to the tripper arm. All of this mechanism and other parts hereinafter mentioned are preferably mounted and incased within a box or housing 46 of concrete or other suitable material located under the rails.

The cable 10 is housed within a line of

pipe 17 between the boxes 46, and at the rear end thereof is connected to a piston or plunger 18 slidably mounted in a cylinder 19 and normally urged by a spring 20 so as to maintain a tension on the cable and normally urge the signal and its connected mechanism into their retracted positions. The cable 10 is connected to its signal by means of a bell crank lever 21 and a link 22, the latter of which has its outer end attached to the crank 23 formed on the shaft 2. It is essential in a system of this kind that each tripping mechanism be held in its depressed position after its depression by the first wheel of the train passing thereover, so as not to be intermittently actuated by successive wheels, and also so as to retain the signal in its shifted position a predetermined length of time after the train has passed said tripping mechanism. To this end, locking mechanism is provided for securing the tripper arm 5 in its depressed position.

The locking mechanism herein shown comprises a pawl 24 pivoted at 25 on the cylinder 15 and normally urged by a spring 26 to engage shoulders 27 formed on the plunger 14. The releasing means for the locking mechanism comprises a cable or link 28 connecting the pawl 24 with the cable 10 which leads to the adjacent signal whereby the drawing of the cable 10 to shift the adjacent signal causes the cable 28 to retract the pawl 24 and release the plunger 14, whereby the rearward signal to which said tripper arm is attached is permitted to return to its normal or neutral position.

If preferred, another form of means, such as that shown in Fig. 5, may be used for retaining the tripper arm 5 in its depressed position. The means shown in this figure comprises a piston 14' operating in a cylinder 15', with which it has air-tight connection, and connected to the tripper arm 5 by means of a link or pitman 16'. The piston is provided with a valve 29 which is arranged so that when the piston is depressed, the air readily passes from the under side thereof, but allows for a gradual admission of air to the under side when the spring 13' tends to restore the tripper arm to its normal position. The valve 29 may be arranged so as to be set to require any desired length of time to elapse before the tripper arm 5 can be fully restored to its normal position. This form of means may be substituted generally for that shown in the other figures, and even where the form shown in said other figures is preferred, this auxiliary means is used at the forward terminal of the signal system, since it does not require the operation of a tripper arm in advance in order to be restored to its normal position.

In order to prevent the intentional or accidental passing of a signal by a train, means are provided adjacent to each of the tripper

mechanisms, adapted to be operated thereby when the adjacent signal is set against the train, so that upon the actuation of said tripper mechanism, said means will cause the setting of the air brake mechanism on the train. This means comprises a lever 30 pivoted at 31 and having a pin (32) and slot (33) connection with a link 34 connected to a member 35 shiftably mounted on the cable 10. The forward end of the member 35 is provided with a series of shoulders 36 which are adapted to be engaged by a bell crank lever 37 pivoted at 38 and connected to the link 16 which connects the tripper arm 5 with the plunger 14. A spring 39 normally urges the member 35 rearwardly so as to move the shoulders 36 out of position to be engaged by the bell crank lever 37. A shoulder 40 on the cable 10 is arranged to engage the member 35 so that when said cable is shifted for setting the adjacent signal, the member 35 is advanced sufficiently to bring the shoulders 36 into position to be engaged by the bell crank lever 37, whereupon a subsequent depression of the tripper arm 5 will actuate the bell crank lever 37 so as to shift the member 35 forwardly still farther and thereby move the lever 30 to a vertically disposed position.

The upper end of the lever is provided with a shoulder 41 which, together with the lever 30, is disposed so that when the lever is in its elevated or vertical position, it will be in position to engage an arm (not shown) on the engine, which is connected to a valve 100 in the air brake system. This arm is normally arranged so that if engaged by the shoulder 41 on the lever 30, the valve will be shifted so as to open the train pipe and set the brakes automatically, and bring the train to a stop. A pawl 42 is arranged adjacent to the lower end of the lever 30, so that when the lever is shifted to its elevated or vertical position, said pawl will engage a pin or shoulder 45 on the lever and retain it in its vertically disposed position. The slot 33 in the link 34 is of sufficient length so that the member 35 may be returned to its normal position by the spring 39, while the lever 30 remains in its elevated position. This provision for an automatic return of the member 35 while the lever 30 remains in its elevated position is made so as to require a manual resetting of the lever 30 by a member of the crew of the train which has been brought to a stop by having attempted to pass a signal set against it. The means for returning the lever 30 to its retracted position comprises a lever 43 attached to the shaft 44 to which the pawl 42 is rigidly connected so that when the lever 43 is shifted, it retracts said pawl and allows the lever 30 to be depressed into its retracted position.

The signaling mechanism herein described is equally suitable for use in operating cross-

ing signals for warning vehicles and pedestrians of the approach of a train. When thus applied, only a slight modification of the connections is required, as will appear from Fig. 4. In such case, the tripper arm 5 is located at the desired distance back from the crossing, and the signal 1 is located at the crossing. The cable 10 is connected to the drum 9 so as to be wrapped around the upper side thereof. The tripper arm may be held in its depressed position by the pawl and ratchet means shown in Fig. 1, or by the air valve means shown in Fig. 5. In case the former is used, an auxiliary tripper arm is placed at the farther side of the crossing, which is connected by a cable 47 so as to retract the pawl after the train has passed the crossing and allow the signal and tripper arm to be returned to their normal positions.

It will also be obvious that the means for operating the crossing signal may be combined with the signal system for trains.

The operation of the device shown in Figs.

25 1 to 5 inclusive, is as follows:

Assume that the train is in the block between the signals A and B, and approaches and passes over the tripping mechanism adjacent to the signal B. The depression of 30 the corresponding tripper arm 5, through the action of the links 7 and 8, revolves the drum 9 so as to wind the cable 10 there-around. The drawing of the cable shifts the signal A so as to set it against a following train approaching the block between the signals A and B. The tripper arm 5 is locked in its depressed position through the engagement of the pawl 24 with one of the shoulders 26. The signal A is therefore 35 held in its "set" position until the train passes out of the block between the signals B and C. As the train passes out of said block and depresses the tripper arm 5 adjacent to the signal C, the corresponding drum 40 9 is rotated so that the cable 10 connecting it with the signal B is drawn to set the signal B. The drawing of the cable 10 retracts the pawl 24, whereupon the spring 13 restores the tripper arm adjacent to the signal 45 B to its normal position and allows the spring 20 acting on the piston 18 to restore the signal A to its neutral position, whereupon the block between A and B is "cleared."

50 When a following train approaches the block where the signal is set against the train, the engineer is supposed to stop and await the resetting of the signal to its "cleared" position. The shifting of a signal into its signaling position causes the member 35, mounted on the corresponding cable, to be shifted forwardly so that the shoulders 36 are moved into position to be engaged by the bell crank lever 37. If, 55 therefore, the engineer should intentionally

or accidentally ignore the signal and pass the same, the tripper arm adjacent thereto would be depressed, whereupon the shifting of the bell crank lever 37 would move the member 35 forwardly and shift the lever 30 70 into its elevated position. The shoulder 41 on the lever 30 would then be in position to engage the arm connected to the valve in the air brake system of the train, so as to shift said arm for setting the valve to release the 75 air and cause the brakes on the train to be set and bring the train to a stop.

Such a depression of the tripper arm 5 would result in its being locked and at the same time set the next signal to the rear of 80 the block into which the train had improperly entered, so that a train subsequent to it would be warned that the forward block was occupied.

The air valve on the engine is placed in 85 a position under the train and has no connection with any of the mechanisms in the cab, so that the engineer cannot restart his train until he has gotten down out of the cab and obtained access to said air valve and 90 reset the same in its normal position. At the same time, the engineer would be required to reset the lever 30 before he proceeded with his train. This he could do only in case the preceding train had passed out of the 95 previous block so as to return the signal which he had improperly passed, to its neutral position. When this has taken place, the engineer may shift the lever 43 so as to retract the pawl 42, whereby the lever 30 100 is released so that it may be depressed into its neutral position.

In the modified form of signal-operating mechanism shown in Figs. 6, 7, and 8, the tripper arm 5 is arranged adjacent to the 105 rail 6 so as to be actuated by a train passing thereover, said arm being normally urged upwardly by means of the spring mechanism within the casing 15 so as to be engaged by the flange of a wheel on the train. 110 The shaft 2 of the target 1 extends downwardly into the box 46 and is provided with a crank 48. The means for shifting the target 1 comprises a shaft 49 journaled in the framework of the mechanism so as to be 115 rotated in its bearing and to be shifted longitudinally with respect to the rail 6. One end of the shaft 49 is connected to the crank 48 by means of an arm 50 and a link 51 so that the rotation of the shaft 49 through an 120 arc of about 90° will rotate the shaft 2 a corresponding amount whereby the target 1 will be shifted to the desired position. The shaft 49 is split at a point near the arm 50 and is provided with a coupling 52, one 125 end of said coupling being rigidly secured to one section of said shaft and the other end of said coupling having a pin-and-slot connection with the other section of said shaft. By means of the coupling 50, both 130

sections of the shaft 49 are adapted to be rotated in unison, but due to the pin-and-slot connection, the longitudinal shifting of the forward section will not affect the rear section of the shaft.

- 5 A curved arm 53 is rigidly mounted on the shaft 49 and is disposed so as to be shifted by the bell-crank 54 through depression of the tripper arm 5. The bell crank 10 lever 54 is pivotally mounted at 55 and operatively secured to a lug 56 rigidly mounted on the plunger or link 16. When the tripper arm 5 is depressed, the downward movement of the plunger 16 will shift the bell 15 crank lever 54 so as to coact with the arm 53 for rotating the shaft 49 through an arc of about 90° and also shifting the forward section of said shaft longitudinally with respect to the rail 6.
- 20 The restoration of the tripper arm 5 to its normal position will not shift the arm 53 back to its inoperative or normal position. Means are therefore provided for accomplishing this result, as for example a manually-operated lever 57 pivotally mounted 25 on a shoulder 58 secured to the framework of the mechanism. The lower end of the lever 57 is connected to the shaft 49 by means of a pair of links 59 so that the shifting of the lever 57 will rotate the shaft 49. A pulley 60 is rigidly mounted on the forward end of the shaft 49 so that if desired said shaft may be rotated the required distance by means of a chain or cable.
- 30 The lever arm 30, which is adapted to cause the setting of the air brake mechanism on the train, is pivoted at 61 and has a pin-and-slot connection with a link 62 shiftably mounted on the shaft 49. A shoulder 35 63 is formed on the shaft 49 adjacent to a corresponding shoulder formed on the link 62 so that the longitudinal shifting of the shaft will shift the upper arm of the lever 30 to its vertical or operative position.
- 40 When the lever is shifted to its vertical position, the arm 64 is urged inwardly. The shoulder 65 thereby engages the lever 30 to prevent it from being accidentally returned to an inoperative position. A shoulder 66 45 is formed on the framework beneath the rails 6 for limiting the movement of the lever 30 when it is shifted to its vertical position. A ring 67 is secured to the shoulder 65 for manually urging the spring arm 50 64 outwardly when it is again desired to lower the lever 30.

When a train has passed over a signal mechanism which was set against it, the engineer is required to manually reset the 55 arm 30 and to shift the lever 57 so as to restore the hook-shaped arm 53 to its initial position.

Although certain specific embodiments of 60 this invention have been herein shown and 65 described, it will be understood that numer-

ous details of the construction shown may be altered or omitted without departing from the spirit of this invention as defined by the following claims.

I claim:

1. In a railroad signal system, the combination of a signal, a tripper arm arranged adjacent to the track in position to be actuated by trains passing thereover, a cable leading from said signal to a point adjacent 70 to said tripper arm, a drum journaled adjacent to said tripper arm and adapted to have said cable wrapped therearound, and a link connection between said drum and tripper arm whereby the depression of said tripper 75 arm rotates said drum.

2. In a railroad signal system, the combination of a signal, a tripper arm arranged adjacent to the track in position to be actuated by trains passing thereover, a cable 80 leading from said signal to a point adjacent to said tripper arm, a drum journaled adjacent to said tripper arm and adapted to have said cable wrapped therearound, a link connection between said drum and tripper 85 arm whereby the depression of said tripper arm rotates said drum, and resilient means attached to the other end of said cable and adapted to urge said cable to restore the parts connected thereto to their normal positions.

3. In a railroad signal system, the combination of a signal having a cable connected thereto, means for shifting said cable to operate said signal, a tripper arm arranged adjacent the track in position to be actuated by trains passing thereover, an air-valve operating lever pivoted adjacent said tripper arm, a member connected to said operating lever and adapted to be actuated 100 for shifting the same, mechanism on said tripper arm adapted to engage and shift said member, means normally urging said member out of position to be engaged by said mechanism, and other means on said cable adapted to shift said member into 105 position to be engaged by said mechanism.

4. In a railroad signal system, the combination of a signal having a cable connected thereto, means for shifting said cable 110 to operate said signal, a tripper arm arranged adjacent the track in position to be actuated by trains passing thereover, an air-valve operating lever pivoted adjacent said tripper arm, a sleeve carried by said cable 115 and connected to said air-valve lever, mechanism on said tripper arm adapted to engage and shift said sleeve, means normally urging said sleeve out of position to be engaged by said mechanism, a shoulder on said cable 120 adapted to engage said sleeve whereby the drawing of said cable shifts said sleeve into 125 position to be engaged by said mechanism.

5. In a railroad signal system, the combination of a signal having a cable com- 130

5 nected thereto, means for shifting said cable to operate said signal, a tripper arm arranged adjacent the track in position to be actuated by trains passing thereover, an air-
5 valve operating lever pivoted adjacent said tripper arm, a sleeve carried by said cable and adapted to be actuated by said tripper arm for shifting said air-valve lever, one end of said sleeve having a pin and slot
10 connection with said air-valve lever, a shoulder formed on the other end of said sleeve, a bell crank lever connected at one end to said tripper arm, a lug formed on the other end of said bell crank lever and adapted
15 to engage said shoulder for shifting said sleeve, said sleeve being shiftable in one direction by said cable so as to shift said shoulder into position to be engaged by said lug, and a spring normally urging said
20 sleeve in the opposite direction so as to shift said shoulder out of position to be engaged by said lug.

6. In a railroad signal system, a combination of a plurality of signals located at intervals along a track, a corresponding number of tripper arms also located at intervals along the track and positioned so as to be actuated by the passing of trains thereover, cables connecting each of said signals with a tripper arm located in advance thereof along the track whereby the successive actuation of said tripper arms causes the successive shifting of the respective signals into and out of signaling positions, a shoulder carried by each of said tripper arms, a pawl located adjacent to each of said tripper arms and normally urged to engage the respective shoulders for holding said tripper arms in their depressed positions, and mechanism connecting the pawl of one tripper arm with another tripper arm located in advance of said tripper arm whereby the depression of said other tripper arm for shifting the signal connected thereto simultaneously retracts said pawl and releases said first tripper arm so as to permit the signal connected to said tripper arm to be returned to its normal position.

7. In a railroad signal system, the combination of a signal, a tripper arm arranged adjacent to the track in position to be actuated by trains passing thereover, a cable leading from said signal to a point adjacent to said tripper arm, means connected to said cable and actuated by said tripper arm for drawing said cable so as to operate said signal, a second tripper arm arranged adjacent the track and contiguous to said signal, an air-valve operating lever mounted adjacent to said second tripper arm, a connection between said second tripper arm and said lever adapted to permit said lever to be shifted into its operating position when said second tripper arm is depressed, said connection including coacting mechanism normally
65

urged out of coacting relation, and means on said cable adapted to shift said coacting mechanism into coacting relation.

8. In a railroad signal system, the combination of a signal, a tripper arm arranged adjacent to the track in position to be actuated by trains passing thereover, a cable leading from said signal to a point adjacent to said tripper arm, means connected to said cable and actuated by said tripper arm for drawing said cable so as to operate said signal, a second tripper arm arranged adjacent the track and contiguous to said signal, an air-valve operating lever mounted adjacent to said second tripper arm, a connection between said second tripper arm and said lever adapted to permit said lever to be shifted into its operating position when said second tripper arm is depressed, said connection including coacting mechanism normally urged out of coacting relation, means on said cable adapted to shift said coacting mechanism into coacting relation, and means for retaining said lever in its operating position independently of said shifting mechanism.

9. In a railroad signal system, the combination of a signal, a tripper arm arranged adjacent to the track in position to be actuated by trains passing thereover, a cable leading from said signal to a point adjacent to said tripper arm, means connected to said cable and actuated by said tripper arm for drawing said cable so as to operate said signal, a second tripper arm arranged adjacent the track and contiguous to said signal, an air valve operating lever mounted adjacent to said second tripper arm, a connection between said second tripper arm and said lever adapted to permit said lever to be shifted into its operating position when said second tripper arm is depressed, said connection including coacting mechanism normally urged out of coacting relation, means on said cable adapted to shift said coacting mechanism into coacting relation, means for retaining said lever in its operating position independently of said shifting mechanism, and manually operated mechanism for retracting said retaining means.

10. In a railroad signal system, a combination of a plurality of signals located at intervals along the track, a tripper arm located adjacent to each of said signals, cables connecting each of said signals with the tripper arm which is located adjacent to the signal next in advance along the track, an air-valve operating lever pivoted contiguous to each of said tripper arms, a member connected to each of said air-valve levers and adapted to be actuated for shifting the same, means on each of said tripper arms adapted to engage the respective members for actuating said members so as to shift said air-valve levers when the respective tripper arms are depressed, each of said members being

normally urged out of position to be engaged by the means on the respective tripper arms, and mechanism on each of said cables adapted to shift the respective member into position to be engaged by the means on the respective tripper arm, whereby the shifting of one signal into signaling position shifts

the member which connects with the lever for the adjacent tripper arm into position to be actuated by said adjacent tripper arm. 10

Signed at Chicago this 21 day of Feb., 1919.

MAURICE W. REEDY.
